UNITED STATES PATENT OFFICE.

GEORGE E. MARLATT, OF PASADENA, CALIFORNIA.

TYPOGRAPHICAL MACHINE.

Application filed October 5, 1926, Serial No. 139,718. Renewed July 5, 1928.

My invention relates to typographical machines of the linotype class in which circulating matrices are released by keyboard means from a storage magazine and assembled in a line in the order of their release, the assembled line transferred to a position in front of a mold in which a cast of type metal is made against the line of matrices and the matrices then returned to their individual channels in the magazine from which they were released.

The class of machines above referred to is differentiated into several types or models according to the special purposes and requirements for which they are designed. For example, among recent developments is the two-magazine "mixer" type of machine in which matrices from two full-length magazines may be mixed in a line in the assembling operation and automatically sorted according to font in the distributing operation for return to their proper magazines. In this type of machine the magazines remain in fixed position in the machine and the conditions are such that if the number of magazines were increased beyond two, mechanical complications and assembling difficulties would result. In another type of machine the magazines are in a movable stack or column and only one of the magazines at a time may be brought to operative position, the mixing feature being sacrificed to the increased number of magazines. It has also been proposed to increase the capacity of such machines by storing two fonts of matrices in a single magazine, as explained in my co-pending application Serial No. 59,299. This present disclosure is directed to means for combining in a single machine the desirable features of the several types of machines above outlined, especially with regard to the assembling operation.

In the accompanying drawings:

Fig. 1 is a right-hand elevation showing the relation of the assembler-entrance throat to the magazines when the throat and associated mechanism are in non-operative position to permit shifting of the magazines; Fig. 2 shows two lower magazines in operative position, with the assembler-entrance throat in position to conduct matrices from the lowest magazine; Fig. 3 shows two upper magazines in operative position, with the assembler entrance throat in position to conduct matrices from the lowest of the two magazines and with the escapement-operat-

ing reeds raised to co-operate with a form of escapement differing from the form shown as operative in Fig. 2; Fig. 4 is similar to Fig. 3, with the assembler-entrance throat in position to conduct matrices from the highest magazine; Fig. 5 is a perspective view of the assembler-entrance throat and associated mechanism.

Fig. 6 is a perspective view of a fragment of one of the magazines showing in series the escapement openings from and through means of which the matrices are released; Fig. 7 is a sectional view taken on the line 7-7 of Fig. 3 and shows an elaboration upon the form of escapement shown in Fig. 6.

By way of example I have selected a showing of four magazines arranged in a movable stack or column. The method of moving the column is immaterial and may be similar to any method heretofore employed or proposed. An object in view is to arrange the magazines compactly and uniformly spaced apart in the stack so that any two magazines may be moved to operative position in register with two corresponding matrix-releasing planes, and matrices from any two adjoining magazines may be mixed in an assembled line. In the group of four magazines, the two upper magazines may be an operative pair, the two lower magazines may be an operative pair, or the two middle magazines may be an operative pair, all according to the position of the stack of magazines. The magazines are also interchangeable or transposable in the stack, so that any two magazines may be associated in mixing position. Thus, if the magazines be considered as numbered, from 1 to 4, six different groupings are possible for mixing purposes, as follows: 1-2, 1-3, 1-4, 2-3, 2-4, 3-4. Figs. 1 to 3 show the magazines arranged in one order in the stack, and Fig. 4 shows them in a different order as numbered from 1 to 4.

I have selected the form of matrix-escape-ment described in my co-pending application Serial No. 139,721 as the form best adapted to present purposes. As explained in said application, this escapement may be merely an opening A through the floor of each matrix channel, through which opening the escapement reeds D act directly upon the matrices to lift them out of the opening for release from the magazine; or, the reeds may act upon an intermediate escapement

element B or C for similarly releasing the matrices. In the present case, those magazines employing the escapements B and C may be considered as containing two fonts 5 of thin matrices arranged in alternating magazine channels, the one form B of escapement alternating with the other form C, one form controlling the release of one font of matrices and the other form controlling the release of another font. When the escapement opening A is in operative position the actuating reeds D must be raised to compensate for the omission of the escapements B—C, and the mechanism to be described 10 automatically raises or lowers the reeds D according to the forms of escapement on the pairs of magazine moved to operative position.

Referring to Fig. 1, the upper portion E 20 of the assembler entrance throat is movable from one to another of two operative positions associated with a pair of magazines, and for this purpose it is pivotally seated on a shaft I supported on top of the rigid portion F of the assembler entrance throat. The lower portion (shown in section) of the throat E is solid across its length except for grooves E¹ to accommodate the throat partitions G; but the upper portion thereof 25 has interstices E² extending from its upper end down to the solid portion and merging with the grooves E¹. These interstices are occupied by the partitions G and the partitions are formed as at G¹ on a radius from 30 the pivotal point of the throat E to prevent the throat from leaving its seat F¹. This construction is such that a series of smooth and unbroken channels occurs between the partitions G regardless of the position of 35 the throat E. In Fig. 1 the throat E is shown in a middle position (as moved from its upper position) to permit the movement of the stack of magazines; in Fig. 4 it is in register with the upper magazine of an operative pair, and in the other "figures" 40 it is in register with the lower magazine of an operative pair. When in its upper position the throat E does not reach to the upper operative magazine, therefore I provide a 45 stationary bridge H over which the matrices pass in their travel from the magazine and through the assembler throat, the bridge being supported by the partitions as best shown in Fig. 5. The partitions are rigidly 50 secured to the rigid portion F of the throat. The throat E is movable manually but 55 indirectly through the instrumentality of arms J secured to the shaft I at each end thereof. The arm J is provided with a 60 circular slot J¹ which is engaged by a pin E³ carried by the throat E. An extreme 65 downward movement of the arm J will move the throat E to its upper position and an extreme upward movement thereof will move 70 the throat to its lower position.

Each escapement-actuating reed is in two parts. The lower part K leads from the keyboard (not shown) with which it may be connected in any suitable manner. It is provided with a slot K¹ by means of which the series of reeds are suspended from and guided on a rod K² resting in a groove across the length of a shift plate L. The edge of the shift plate L is notched to receive and space apart the upper ends of the lower reeds 75 K. The slots K¹ are of sufficient length to permit the requisite upward stroke of the reeds when the keys of the keyboard are depressed. The upper reeds D are provided with four shoulders, two of which, D¹ and D², co-operate with the lower reeds K when the throat E and reeds D are in raised position, and the other two, D³ and D⁴, when the throat and reeds are in lowered position. The shoulders D¹ and D² are above the lower 80 reeds K when the simplified form A of escapements are in use and the reeds D are correspondingly raised, and when the reeds D are lowered to accommodate the other form B—C of escapement the shoulders D³ or D⁴ are above the lower reeds K. In order 85 that the reeds D may automatically attain any one of these four positions according to the position of the throat E and according to the form of escapement in use, I provide as 90 follows:

When the throat E and reeds D are in lowered position the reeds are supported on a rod O¹ carried by a series of levers O, and the reeds remain thus supported while associated with the escapements B—C. When raised to the escapement-A position they are supported on the rod M¹. Their position relative to the two forms of escapement (A or B—C) is under control of a pair of levers 100 N secured to a shaft N¹ supported in extensions G² of the series of partitions G. The levers N may bear against either a stud J² or J³ according to the position of the lever J from which these studs project, or both 105 studs may clear the lever as in Fig. 1 and it will then rest against a fixed stop F². A slight movement of the arm J (from the position shown in Fig. 3) as permitted by 110 the length of the circular slot J¹ will move the upper stud J³ away from a shoulder N² on the vertical arm of the lever N, and the horizontal arm of the lever N will therefore 115 be permitted to drop, carrying the series of reeds D to their lower position for association with the escapements B—C. This position of the reeds is shown in Fig. 2. It will be noted that in this position any material further movement of the lever will be prevented by the stop F², hence the outer end 120 of the arm J may be moved an additional distance downward without materially affecting the position of the lever N. This additional movement of the arm J is for the 125 purpose of moving the ends of the reeds D 130

from a position beneath the series of escapements B to a position beneath the series of escapements C. For this purpose the reeds are centrally pivoted on the rod O¹ carried by the series of levers O and the series of levers M, carry a rod M² which is engaged by the angular end P¹ of a link P controlled by the arm J. The additional downward movement of the outer end of the arm J moves the link P rearwardly and the levers M are thus permitted to swing rearwardly about their pivot M³, carrying the lower ends of the reeds D a corresponding distance and moving their upper ends in an opposite direction to a position beneath the series of escapements C, all as shown in dotted lines in Fig. 2. With the parts in this dotted position the lower end of the circular slot J¹ contacts with the stud E³ and further downward movement of the arm J will raise the throat E and reeds P to their upper position in operative relation to an upper magazine. When this movement ensues the upper ends of the reeds D move forward from their position shown dotted in Fig. 2 in advance of their lower ends (which swing an additional distance rearward) so that the reeds may clear the escapements C before being raised.) To permit this action a lower link Q which connects the throat E with the rod M² has a slot Q¹ of sufficient length to permit the levers M to lag when the throat E is initially moved upwardly. But an upper link R which connects the throat E with the reed-supporting levers O serves to immediately swing the upper ends of the reeds forward when the throat E is initially moved upwardly. When the reeds D are being raised they are suspended only on the upper supporting rod O¹, the lower rod M¹ serving merely as a guide in the slots D². The upper series of levers O are supported on a pivot shaft O³ carried by extensions G² of the series of partitions G. The only purpose in making the levers M in a series of short sections is for convenience in drilling the holes for accommodating the three shafts or rods on which they are assembled. The levers M and O are provided with notches M⁴ and O⁴ respectively for spacing apart the reeds D. Near their upper ends the reeds D are additionally guided in notches E⁴ formed in a series of extensions E⁶ of the movable throat E.

In Fig. 4 the levers O are shown as swung to their extreme upward position in order to place the reeds D in their escapement-A position, but this extreme movement does not occur if the escapements B—C are employed on the upper magazine. As a control in this connection the link R has a pin R¹ and slot R² connection with the throat E. When the levers O are in raised position the circular slot R² is eccentric relative to the pivot rod O², hence if the pin R¹ is moved downward in the slot R² the levers O and reeds D will be correspondingly lowered to co-operate with the escapements B—C. The pin R¹ controls and is also controlled by a lever T centrally pivoted on the throat E. Those magazines employing the escapement A have a projection T¹ with which the lever T contacts when the throat E is raised, thus moving the pin R¹ to the upper end of its slot and raising the reeds D to their escapement-A position. But in the absence of the projection T¹ a spring U¹ keeps the horizontal arm of a lever U downward against the lever T and the reeds are accordingly retained in their lower position and in operative relation to the escapements B—C. The manner of shifting the reeds from one to another of the escapements B or C when the throat E is in its upper position is similar to that explained in describing the lowered position of the throat, the stud J³ serving through the connections described to shift the reeds about their central pivot O¹. In Figs. 3 and 4 the levers T and U are omitted, only the holes T² and U² for their pivot screws T³ and U³ being shown.

When the reeds D are in their escapement-A position in connection with an upper magazine the position of the lever N is such that the shift plate L is out of control thereof, therefore I provide a centrally-pivoted lever V for shifting the reeds K beneath the shoulder D¹ when the reeds D are in raised position as controlled by the pin R¹ and slot R². When the pin R¹ is at the upper end of its slot the end of the link R engages the angular upper end of the lever V and the lower end thereof is forced rearwardly against the shift plate L and moves the plate to shift the reeds K¹ beneath the appropriate shoulder D¹ on the reeds D. A spring L¹ serves to return the plate L when it has been freed from control by the lever V or by the lever N as elsewhere explained. The lever V is pivoted on a screw V in a member Y and when not under control of the link R it hangs idle as in Fig. 3. In Figs. 1 and 2 only the hole V² for the pivot screw is shown.

As a preventive against attempting to raise the reeds D to their escapement-A position when the throat E is in its lowered position and a magazine having the escapements B—C is in use, I provide as follows: Each magazine employing the escapements B—C carries a projecting stop S¹; an arm S is pivotally connected to the arm J and contacts with the stop S¹ to limit the upward movement of the arm J when lowering the throat E or thereafter. With the arm J thus limited the stud J³ cannot move downwardly a sufficient distance to move the arm N, hence the reeds D cannot be raised above their escapement B—C position; but a slight return movement of the arm J will serve to

shift the reeds D from the escapements B to the escapements C as elsewhere explained. A spring F³ (Fig. 4) is carried across the pivot point I with the movement of the 5 throat E and serves to retain the throat in its upper position. The arm S rests and slides on the throat E.

When the throat E is in its lower position and reeds D are raised to their escapement-A position (Fig. 3) by reason of the 10 contact of the stud J³ with the lever N, the lower end of the lever N forces the shift plate L forward to place the lower reeds K beneath the shoulder D³ of the upper reeds, 15 and when the reeds are lowered to their escapement B—C position (Fig. 2) the spring L¹ serves to restore the reeds to a position beneath the shoulder D⁴. With the 20 throat floor in lowered position and the reeds D in escapement-A position as in Fig. 3 the movement of the stud J⁸ away from the shoulder N² will cause the reeds D to drop to clear the end of the magazine before the end of the slot J¹ engages the pin E³ 25 to raise the throat floor E.

Substantially all of the mechanism so far described is in duplicate at opposite sides of the machine, as indicated in the perspective figure of the drawings. In order that the 30 parts may operate in a united and balanced manner, I provide an operating handle W midway between the two sets of mechanism. This handle W is rigidly secured to a shaft W¹ and may have suspended therefrom a swinging grip W² of sufficient length to be readily reached by an operator at the keyboard. At its opposite ends the shaft W¹ bears in the arms J. Toothed sectors X are 35 secured to the shaft W¹ just inside the arms J and mesh with similar sectors Y secured to the outer partitions G. With the handle W and gears X thus rigid on the shaft W¹, any movement of the handle will cause the arms J and parts controlled thereby to move 40 in unison regardless of the fact that the two sets of mechanism are widely spaced apart at opposite sides of the machine. In order that the shaft W¹ may not interfere with opening the assembler front plate, I 45 divide this plate into two parts Z and Z¹, each part being provided at opposite ends with brackets Z² pivoted on extensions G³ of the outer partitions G. A circular opening in the extensions G³ permits the 50 requisite movement of the shaft W¹ about the pivotal point I when the handle W is moved.

Having thus described my invention, what I claim as new and desire to secure by Letters Patent, is: In a typographical machine—

1. In combination, superposed matrix-magazines, an assembler-entrance throat having an angular portion thereof pivotally movable for conducting matrices from a selected magazine, a series of throat partitions

between which matrices are conducted from said magazines, and the specified construction whereby the angular portion of said throat may be moved from one to another operative position regardless of the fact that 70 said throat partitions are rigid and continuous.

2. In combination, superposed matrix magazines, a series of rigid throat partitions between which matrices are conducted from 75 said magazines, a bridge mounted on said partitions in register with the upper magazine, and a throat floor movable to and from a position in register with said bridge or the lower magazine, selectively, for conducting matrices from said magazines.

3. In combination, an upper and a lower matrix magazine, an assembler-entrance throat having an angular portion thereof pivotally movable for receiving matrices 85 from either of said magazines, selectively, a series of rigid throat partitions embracing both of said magazines, and a series of interstices in said angular throat portion intersected by said partitions in order to permit 90 the movement of said angular throat portion.

4. In combination, superposed matrix magazines, a throat movable from one to another of said magazines, selectively, for conducting matrices therefrom, matrix escapements of different form on said magazines, escapement-actuating reeds movable with said throat from one to another form of escapement, and means whereby said reeds will be caused to be raised and lowered different distances according to the form of escapement on the magazine with which said 100 throat is selectively associated.

5. In combination, superposed matrix magazines having escapements thereon for releasing matrices therefrom, reeds for actuating said escapements, an assembler entrance throat having a rigid and vertical lower portion and a movable and angular upper portion, means for moving said upper portion from one to another of said magazines selectively, and means whereby said reeds will be caused to move therewith and under control to the escapements on the magazine selected for use.

6. In a typographical machine having superposed matrix magazines with matrices therein and capable of release therefrom, an angular throat through which matrices are conducted from said magazines and a 110 series of rigid throat partitions common to and embracing said magazines, means for rendering said throat capable of conducting said matrices from either of said magazines, said means consisting of rendering the floor 115 portion of said throat movable pivotally from one to another of said magazines without varying its length or shape.

7. In a typographical machine having inner and outer operative inclined matrix mag- 130.

azines from which matrices may be released to and through a raceway divided by rigid partitions embracing both of said magazines, a vertical wall for said raceway, an angular floor therefor extending in direct continuation of said wall to a position in direct communication with the inner one of said magazines, and a structure permitting said floor to be moved from direct communication with said inner magazine to a position in communication with said outer magazine and vice versa, at will, in order that said single angular throat floor may serve for conducting matrices from either of said magazines regardless of the rigidity of the raceway partitions which embrace said magazines.

8. In a typographical machine, in combination, inner and outer matrix magazines each having a series of matrix-releasing escapements associated therewith, a delivery throat floor E movable from one to another of said magazines selectively for conducting matrices therefrom, a series of escapement actuators supported independently of said throat floor and movable under control

thereof from one to another of said series of escapements with the movement of said throat floor, and a series of slots E⁴ carried by said throat floor for spacing apart the ends of said escapement actuators when associated with either of said series of escapements.

9. In a typographical machine having superposed matrix magazines each employing a series of escapements for controlling the release of matrices therefrom, an upper pivotally-mounted series of escapement-actuating reeds D movable from one to another of said series of escapements selectively, a lower series of reeds K for actuating said upper series of reeds, and means whereby a direct operative connection will be maintained between said upper series and said lower series of reeds regardless of the position of said upper series of reeds relative to said two series of escapements.

Signed at Pasadena, Los Angeles County, California, this 28th day of September, 1926.

GEORGE E. MARLATT.
